FOLDING CHAIR

Alfred F. Vanderminden, Granville, N. Y., assignor to The Telescope Folding Furniture Co., Inc., Granville, N. Y., a corporation of New York

Application November 1, 1949, Serial No. 124,795

4 Claims. (Cl. 155—117)

1.

My invention relates to folding chairs and, more particularly, to a folding chair having unique safety features whereby the possibility of an accidental backward collapse of the chair is substantially eliminated.

An object of my invention is to provide folding chairs that can be rapidly and simply erected, having one or a plurality of adjustments whereby the back thereof may be inclined in different positions and which chairs cannot accidentally collapse backwards.

It is an advantage of my invention that the user of the chair is safeguarded against falling heavily to the ground or catching some part of his body in a collapsing section of the chair as sometimes occurs when ordinary folding chairs collapse. It is a further advantage of my invention that it permits the folding chair to be picked up and moved without the necessity of collapsing the chair or having the chair automatically collapse, and yet it does not interfere with the deliberate collapsing of the chair. My invention forms a fixed part of the chair and need not be removed or adjusted in any way, either to adjust the back of the chair in the normal manner, or to deliberately collapse the chair.

Other objects and advantages will appear hereinafter from the following description and the drawing, in which preferred embodiments of my invention are shown.

Fig. 1 is a general side view of a folding chair.

Fig. 2 is a section taken along the line 2—2 of Fig. 1.

Fig. 3 is a section taken along the line 3—3 of Fig. 2.

Fig. 4 is a section taken along the line 4—4 of Fig. 3.

Fig. 5 is a side view of the rear leg of the folding chair, with parts broken away, showing a modified form of my invention.

It will be understood that in viewing Fig. 1, all of the members shown are located at the near side of the chair, and that generally corresponding identical members are located behind said near members on the far side of the chair.

As shown in Fig. 1, the folding chair 11 comprises a pair of parallel, downwardly extending front leg members 12, joined together near the bottoms thereof by a cross-bar 13. Each leg member 12 is pivotally connected by a pin 14 to a corresponding member of a pair of parallel seat members 15. Disposed beneath the seat members is a pair of a parallel, backwardly and downwardly sloping back-leg members 16. Each back-leg member 16 is pivotally connected by a

pin 14 to a corresponding seat member 15 and front leg member 12. Back leg members 16 are joined together by a cross-bar 17. Each back-leg member is provided on its upper surface with a plurality of notches 18. As seen in Fig. 1, the notches on the near member 16 are oppositely positioned to the notches on the far member 16, whereby the notches are paired.

The two seat members 15 are joined together at the fronts and backs thereof by cross-bars 19 and 20 respectively, and a section of canvas 21 is stretched between the seat members 15 and affixed thereto so as to form a seat. This combination of seat members 15, cross-bars 19 and 20, and canvas 21 may be referred to as the seat frame. Pivotally connected to the upper end of each of the front legs 12 by a pin 23 is an arm rest 24. The back end of each arm 24 is pivotally connected by a pin 25 to a back member 26. The arm rests 24 are generally parallel to each other and to the seat frame. The two members 26 are parallel to each other and downwardly extending and are generally parallel to the front legs. Back members 26 are joined together at the tops thereof by a cross-bar 27 and are pivotally connected to the back ends of the corresponding seat members 15 by pins 22. Extending below pin 22 is an integral portion of each back member 26 which may be termed a strut member 28. A cross-bar 29 joins together the two parallel strut members 28. As can best be seen in Fig. 2, cross-bar 29 extends through the strut members 28, thus forming projections 35 extending beyond the outside vertical surfaces. A section of canvas 30 is stretched between back members 26 and affixed thereto so as to form a back rest.

The combination of the two back members 26, the cross-bar 27, and canvas 30 may be referred to as the back frame. It will be understood that an additional piece of canvas 36 may be stretched between cross-bar 27 and cross-bar 20 and between cross-bar 20 and cross-bar 19 so as to reinforce the back frame and the seat frame and enhance the comfort of the sitter.

45. Affixed to each of the two back leg members 16 is a guard 31. As shown in Fig. 3 the left end or first portion 32 of the guard 31 has an end extending into and thereby frictionally affixed to the upper surface of the corresponding back leg member 16. The right end or third portion 33 of the guard 31 has an L-shape, that is, it is bent to the outside and then down to lie against the outside vertical surface of member 16 and driven into and thereby affixed to back leg member 16. 50. The central portion or second portion 34 of the

guard 31 extends lengthwise of the upper surface of the rear leg member and above the plurality of notches 18 thereof. The central portion 34 is elevated a sufficient distance above the upper surface of member 16 so that projection 35 may freely travel therebetween. Cross-bar 29 is affixed to and extends between the strut members 28 and the projections 35 thereof are shown resting in the right hand pair of notches 18.

As shown in Fig. 3 the left end 32 of guard 31 is bent upward adjacent to the left hand notch 18 in member 16 whereby projection 35 is prevented from travelling to the left past the left end of the guard. Thus the left end 32 may be referred to as the closed end of guard 31. The central portion 34 of guard 31 passes above the projection 35, as can best be seen by a comparison of Figs. 3 and 4. Thus when the projections are located in any pair of notches they may move to a limited extent vertically so as to be disengaged from the notches. They may then move either generally to the left or right along member 16, as viewed in Fig. 1. Movement to the left is limited by the closed end of wire guard 31. As can best be seen by a comparison of Figs. 3 and 4, the right ends 33 of the guards 31 are bent to the outside vertical surfaces of the members 16 whereby the movement of projections 35 generally to the right is unrestricted by guard 31. Thus the right end 33 may be referred to as the open end of guard 31. Thus by moving projections 35 to the right from under the guard 31, the chair may be collapsed, in the usual manner, for storage. When the chair is erected as shown in Fig. 1, the projections 35 are located in any one of the pairs of notches 18 and are under the guard 31, it will be seen therefore that backward collapse of the chair is substantially impossible. The presence of the wire guard restricts movement of projections 35 except generally to the right, which produces a forward collapsing of the chair, which is necessary for storage, and which cannot occur when the chair is under load, as by a person sitting therein.

As shown in Fig. 5, a modified form of guard may be affixed to each of the rear legs 16 of a folding chair (not entirely shown) the chair being of the same type as that shown in Fig. 1. In Fig. 5, the modified guard 37 comprises a left end or first portion 38, identically constructed and in like manner affixed to rear leg 16, as is left end 32 of guard 31. The central portion or second portion 40 of the guard 37 extends lengthwise of the upper surface of the rear leg member and above the plurality of notches 18 thereof. The central portion 40 is elevated a sufficient distance above the upper surface of member 16 so that projections 35 of cross-bar 29 may freely travel therebetween. In addition the central portion 40 is sufficiently long so that cross-bar 29 may move to the right to the end of its possible movement relative to the rear leg so that when the chair is completely collapsed forward, the projections 35 are still within the guard. The right end or third portion 39 of the guard 37 has an end bent down from the central portion and driven into the upper surface of the rear legs.

It can be seen that both ends of guard 37 are closed, that is, the projections 35 cannot accidentally remove themselves from beneath the guard, and that the central portion is elongated.

The projections, however, are freely movable within the range necessary to erect and adjust the chairs and to deliberately collapse it, but

movement of the projections which would permit the chair to collapse backwardly is prevented.

It will, of course, be understood that my invention is applicable to other types of folding chairs.

Having thus described my invention, what I claim is:

1. A folding chair comprising a seat frame, a back frame pivoted thereto, a pair of parallel arm members pivoted to said back frame, a pair of parallel, downwardly extending front leg members pivoted to said seat frame and said arm members, a pair of parallel strut members pivoted to said seat frame and having projections thereon, a pair of parallel, backwardly and downwardly sloping back leg members pivoted to said front leg members and having a plurality of pairs of notches therein, said notches being adapted to receive said projections, and a pair of guard members, one guard member being affixed to each back leg member; the combination of the seat frame, back frame and arm members being supported at the front by said front leg members and at the back by the strut members and attached projections lying in one of the pairs of notches of the rear leg members, said projections being disposed to move in a given direction along said rear leg members when the projections are disengaged from the notches and a load is applied generally backward on said back frame, said guard members each comprising a bent wire form having a first portion affixed to the upper surface of one of said back leg members and extending upward therefrom, said first portion being adapted to stop one of said projections against movement in said given direction, and each of said guard members having a second portion continuous with said first portion and extending lengthwise of the upper surface of said back leg member and positioned above said plurality of notches therein, and a third portion continuous with said second portion and having an L shaped portion extending laterally of said second portion and permitting movement of the projection out of operative relation to said guard member.

2. A folding chair comprising a seat frame, a back frame pivoted thereto, a pair of parallel arm members pivoted to said back frame, a pair of parallel downwardly extending front leg members pivoted to said arm members and said seat frame, a pair of parallel strut members extending downwardly from said back frame below said seat frame and having projections thereon, a pair of parallel backwardly and downwardly sloping back leg members pivoted to said front leg members and said seat frame and disposed beneath said projections, said back leg members having a plurality of pairs of oppositely disposed notches in the upper surfaces thereof, said projections being arranged to slide along said upper surfaces and said notches being adapted to receive said projections, and a fixed wire guard member affixed to each back leg member and arranged above said notches therein and above one of the projections, the combination of said seat frame, back frame and arm members being supported in the front by said front leg members for either forward or backward movement and being supported at the back by the said strut members and projections, said projections being disposed for movement in a forward direction along the rear leg members when the projections are disengaged from the notches and a load is applied on said back frame tending to move the same backward, each guard member comprising a first

portion affixed to a rear leg member and adapted to stop the adjacent projection against movement in a forward direction to prevent the backward collapsing of the chair upon dislodgment of said projections from said notches, an elongated second portion overlying said projection and arranged to limit but not prevent upward movement of said projection and to permit movement of said projection under said second portion when said projections are disengaged from said notches, and a third portion affixed to said rear leg member but permitting unobstructed rearward movement of said projections along said rear leg members for forwardly collapsing the chair when said projections are disengaged from said notches.

3. A folding chair comprising a seat frame, a back frame pivoted thereto, a pair of parallel arm members pivoted to said back frame, a pair of parallel downwardly extending front leg members pivoted to said arm members and said seat frame, a pair of projections connected with said back frame, a pair of parallel backwardly and downwardly sloping back leg members pivoted to said front leg members and disposed beneath said projections, said back leg members having a plurality of pairs of oppositely disposed notches in the upper surfaces thereof, said projections being arranged to slide along said upper surfaces and said notches being adapted to receive said projections, and a fixed wire guard member affixed to each back leg member and arranged above notches therein and above one of the projections, the combination of said seat frame, back frame and arm members being supported in the front by said front leg members for either forward or backward movement and being supported at the back by the said projections, said projections being disposed for movement in a forward direction along the rear leg members when a load is applied on said back frame tending to move the same backward, each guard member comprising a first portion affixed to a rear leg member and adapted to stop the adjacent projection against movement in a forward direction to prevent the backward collapsing of the chair upon dislodgment of said projections from said notches, an elongated second portion overlying said projection and arranged to limit but not prevent upward movement of said projection and to permit movement of said projection under said second portion when said projections are disengaged from said notches, and a third portion affixed to said rear leg member but permitting unobstructed rearward movement of said projections along said rear leg members for forwardly collapsing the chair when said projections are disengaged from said notches, said second portion being extended rearwardly to permit complete forward collapsing of said chair without movement of the projections from under the said guards, and said third portion being secured

to the upper surface of said rear leg member to close said guard about said projection.

4. A folding chair comprising a seat frame, a back frame pivoted thereto, a pair of arm members pivoted to said back frame, a pair of downwardly extending front leg members pivoted to said arm members and seat frame, a pair of strut members extending downwardly from said back frame below said seat frame and having projections thereon, a pair of backwardly and downwardly sloping back leg members pivoted to said front leg members and said seat frame and disposed beneath said projections, said projections being arranged to slide along the upper surfaces of said back leg members, and a fixed wire guard member secured to a back leg member and arranged above one of said projections, the combination of said seat frame, back frame and arm members being supported in the front by said front leg members for either forward or backward movement and being supported at the back by the said strut members and projections, said projections being disposed for movement in a forward direction along the said leg members when the projections are disengaged from the notches and a load is applied to said back frame tending to move the same backward, said guard member comprising a first portion adapted to stop said projection against movement in the said forward direction to prevent the backward collapsing of the chair, an elongated second portion overlying said projection and arranged to limit upward movement of said projection and to permit movement of said projection under said second portion whereby said projection is movable rearwardly along said rear leg member for forwardly collapsing the chair, said second portion being extended rearwardly to permit complete forward collapsing of the chair without movement of the projection from under the said guard, and a downwardly extending third portion closing said guard about the projection.
